LOOM HARNESS

Albert J. Kiely and Charles F. Kramer, Philadelphia, Pa., assignors to Steel Heddle Manufacturing Company, Philadelphia, Pa., a corporation of Pennsylvania
Filed Mar. 13, 1962, Ser. No. 179,297
7 Claims. (Cl. 139—82)

This invention relates to loom harness for weaving and more particularly to apparatus for preventing the sidewise displacement of one heddle frame with respect to the others in a weaving loom.

It is the principal object of the present invention to provide simple but effective structure associated directly with the heddle frames for preventing sidewise displacement of one or more of a plurality of heddle frames with respect to the others.

It is a further object of the present invention to provide simple but effective structure on loom heddle frames so that the frames are all urged into edge aligned relation.

It is a further object of the present invention to provide aligning structure on loom heddle frames which urges the frames into aligned relation, and which, in a preferred embodiment, may be applied to heddle frames at the time of their initial construction or subsequently added thereto if desired.

Other objects and advantageous features of the invention will be apparent from the description and claims.

The nature and characteristic features of the invention will be more readily understood from the following description, taken in connection with the accompanying drawings forming part thereof, in which:

FIGURE 1 is a front elevational view of a loom heddle frame in accordance with the present invention;

FIG. 2 is a fragmentary prespective view of a plurality of heddle frames in accordance with the invention;

FIG. 3 is a horizontal sectional view, enlarged, taken approximately on the line 3—3 of FIG. 1; and

FIG. 4 is a vertical sectional view, further enlarged, taken approximately on the line 4—4 of FIG. 3.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to the drawings, a plurality of heddle frames 10 of well-known type are shown, having top and bottom rails 11 and 12 and side struts 13. Spaced respectively below and above the rails 11 and 12, heddle supporting rods 14 and 15 are shown for supporting a plurality of heddles 16 in a well-known manner. The heddles 16 are shown as having central warp eyes 17.

The heddle supporting rods 14 and 15 can be mounted in the heddle frames 10 in any desired manner with intermediate supports (not shown), and if desired can be restrained and held at their ends by resilient locking clips 18 carried by the side struts 13 with locking tongues 19 engaging in locking openings 20 in the rods 14 and 15. The structure just described is well known in the art and is shown merely for purposes of explanation of the present invention.

In order to overcome any tendency of one heddle frame 10 to become displaced sidewise or horizontally, the con-

2

tiguous frames 10 are provided with members having interengaging vertically extending face portions herein-after described, disposed out of the main plane of the heddle frame 10, to urge any frame 10 tending to move sidewise back to a side edge aligned position.

For this purpose, each of the heddle frames 10, on the outer face portion 21 of the side struts 13, is provided with a plurality of vertically spaced recesses 22 for the reception of securing portions 23 of restraining brackets 10 or plates 24. The portions 23 are held in engagement and secured to the side struts 13 in any desired manner, such as by rivets 25 which can also serve to carry the locking clips 18.

The plates 24 have inwardly disposed face portions 26 which, by their engagement with outer side face portions 21 of contiguous side struts 13 on opposite sides, prevent appreciable separate sidewise movement of any of the heddle frames 10. The motion restraining face portions 21 and 26 are disposed in non-parallel and intersecting relation to the main planes of the heddle frames 10 and the heddle rods 14 and 15.

We claim:

1. In a loom having a plurality of contiguous heddle frames, means for reducing sidewise movement of any 25 of the frames comprising members on each of said heddle frames and vertically moved therewith having a vertical face portion in interengaging relation to a vertical face portion of a contiguous heddle frame.

2. A loom as defined in claim 1, in which the heddle 30 frames have side struts and the interengaging face portions are on contiguous side struts.

3. A loom as defined in claim 1, in which the heddle frames have vertical side struts, and one of the face portions is a face of a side strut.

35 4. A loom as defined in claim 1, in which the heddle frames have vertical side struts and one of the face portions is on a bracket carried by one of the side struts.

5. A loom as defined in claim 1, in which the heddle frames have vertical side struts, and said means is provided on contiguous side struts on both sides of said frames.

6. In a loom having a plurality of contiguous heddle frames, each of the frames at each side having members carried thereon with vertical face portions in planes in intersecting relation to the main plane of its heddle frame, said members on contiguous heddle frames having their vertical face portions disposed in meeting relation and preventing sidewise displacement of each heddle frame.

7. A loom as defined in claim 6 in which each heddle 50 frame has side struts with certain of said vertical face portions thereon and plates carried thereon with others of said vertical face portions on said plates.
